UNITED STATES PATENT OFFICE.

SYDNEY COXON, OF LIVERPOOL, AND WILLIAM ALBERT WILLIAMS, OF WALLASEY, ENGLAND, ASSIGNEES TO THE ALADDIN RENEW ELECTRIC LAMP CORPORATION LIMITED, OF LONDON, ENGLAND, A BRITISH CORPORATION.

RENEWAL OF THE FILAMENTS IN METAL FILAMENT ELECTRIC LAMPS.

1,422,747.

Specification of Letters Patent.

Patented July 11, 1922.

Application filed September 2, 1920. Serial No. 407,755.

To all whom it may concern:

Be it known that we, SYDNEY COXON, a British subject, residing at Liverpool, England, and WILLIAM ALBERT WILLIAMS, a 5 British subject, residing at Wallasey, Cheshire, England, have invented certain new and useful Improvements in the Renewal of the Filaments in Metal Filament Electric Lamps, of which the following is a specification.

This invention relates to improvements in the renewal or replacing of the filaments of metal filament electric lamps. Such filaments have previously been renewed by first 15 removing the old spent filament by way of an aperture formed in the tip of the globe, a temporary lower scaffold being then fitted beneath the permanent lower scaffold and the new filament wound on to the upper permanent scaffold, and the lower temporary scaffold, after which the new filament was transferred from the temporary scaffold to the permanent lower scaffold. In some arrangements also a special fitting was used for 25 connecting the ends of the new filament to the leading in wires.

The present invention provides an economical process of effecting the renewal of the metal filament, whereby the temporary scaffold is dispensed with.

The process of the present invention is characterized by the fact that the new filament is wound directly round the upper permanent scaffold wires and the roots of the 35 lower permanent scaffold wires, whereby owing to the considerable rigidity offered by such frail wires at the roots the filament may be mounted directly thereon without the aid of a temporary scaffold. Such a process is 40 applicable when using a straight filament to the renewal of all lamps in which the lower scaffold wires, at or near their base, are sufficiently stiff relatively to the stiffness of the filament to enable the requisite tension to be placed upon the filament to 45 straighten each bight between the upper hooks and the lower scaffold wires in the process of winding.

Preferably, the lower scaffold wires are 50 first bent downwardly close to the roots, the new filament is wound on them and "set," and subsequently the depending loops of the filament are moved from the roots to the outer ends of the lower scaffold wires.

The setting may be effected in a partial 55 vacuum by flashing a current through the filament.

The invention also relates to the manner of connecting the filament to the leading-in wires. According to the invention of an 60 open hooked end is formed on a leading-in wire, the filament is wound several times round the hook and to facilitate trimming off the end of the filament close to the leading in wires a bight or stretch of filament is 65 left extending from the wound hook across to the other leading-in wire. This bight may be readily cut. The wound hook is preferably closed before cutting.

The filament may be readily wound in 70 place by means of an implement consisting of a length of glass tubing having a pointed nozzle through which the filament is threaded. The whole of the operations above described are performed within the 75 lamp bulb, access being gained to the interior thereof by a hole in the bulb. This hole, instead of being central with the tip, as heretofore customary, is preferably disposed substantially eccentric to the axis 80 of the glass stem of the scaffold wires. The implements used in rewiring may therefore be passed up into the bulb clear of the usual wire bead on the glass stem.

The invention is illustrated in the accompanying drawings, in which:

Figure 1 is a view of a lamp showing the arrangement of the metal filament when renewing;

Figure 2 shows the manner of making the 90 first connection to the leading-in wires;

Figure 3 is analogous to Figure 2 showing the manner of making the final connection of the filament to the leading-in wires;

Figure 4 is an inverted plan of Figure 1 95 showing the eccentric disposition of the aperture formed near the tip of the bulb;

Figure 5 is a view of an implement suitable for forming the hooked ends on the leading-in wires;

Figure 6 shows an implement for closing the hook on the leading-in wires; and

Figure 7 illustrates an implement for cutting the filament.

In carrying out the invention, an aperture 105 1 is formed in the tip of the bulb 2 and the old filament removed from the upper and lower permanent scaffold wires, 3, 4 of the

2

lamp in any suitable manner as by washing out. Open hooked ends 5 are then formed on the ends of the leading-in wires 6, 6^a, and the new filament wound on in the following manner. The filament wire is carried over the hooked end of one leading-in wire 6^a, Figure 2, and wound several turns, preferably, round the hooked end of the other leading-in wire 6, leaving a straight length of filament *a* from one leading-in wire to the other. The open hooked end of the leading-in wire 6 round which the filament has been wound is then closed up tightly to make electrical connection therewith. A cutting device is then passed up through the aperture 1 of the lamp and the filament cut between the two leading-in wires 6^a, 6, the loose tail piece *b* of filament being withdrawn. Either previously or at this stage, the lower permanent scaffold wires 4 are bent downwards near the root where they are embedded in the glass stem as shown in the full lines Figure 1. One end of the new filament *c* being now secured to the end 25 of the leading-in wire 6, the filament is carried down and passed close round the root of the first lower scaffold wire 4 and up round the outer hook on the first upper scaffold wire 3, down and under the next lower scaffold wire near its root, and over the next upper scaffold wire hook, and so on round the outer hooked ends of the upper scaffold wire and the inner roots of the lower scaffold wires until the looped formation is completely carried round the upper and lower scaffold wires, the end of the filament being then wound, preferably, several turns round the open hooked end of the remaining leading-in wire 6^a, Figure 3, and then carried 40 across and over the other leading-in wire 6 to leave another straight length *d*. The open hooked end on the wire 6^a is then closed firmly, securing the end of the filament and making electrical connection therewith. 45 The cutting device is then inserted and the filament cut across this straight length. After the filament has been wound in this way a partial vacuum is set up in the lamp and a current flashed through the filament. 50 This operation "sets" the filament. The lower scaffold wires 4 either at this stage or before flashing, are bent upward to their original position shown in dotted lines 4^a Figure 1 and the lower tips of the filament 55 loops are passed radially outward from the roots along the lower scaffold wires 4 until they ultimately spring into engagement with the outer hooked ends of such lower scaffold wires as shown in dotted lines *c*¹, 60 Figure 1. The bulb is then exhausted and sealed in any suitable and usual manner.

Such a process considerably simplifies the operation of rewinding old filament lamps inasmuch as no temporary lower scaffold is 65 required and no special connecting fittings

on the leading-in wires for the new filament, consequently the lamp when rewired by this process bears scarcely any evidence of having been renewed.

In order to facilitate the rewinding of the 70 filament, a short piece of tubing 16, Figure 2, preferably of glass but which may be of other material and having a pointed nozzle 16^a is threaded on the new filament *c*. The hole through which the filament issues from the nozzle is preferably situated eccentrically. In the drawing the tube 16 is shown larger than the preferred size which is about three to five millimeters external diameter. During the operation of winding, this tube 80 serves as a manipulating handle, by means of which the filament may be quite easily passed up through the aperture 1 formed in the bulb and worked round the leading-in wires 6, 6^a, and up and down round the scaffold wires 3, 4 to form the loops. During this operation the scaffold wires 4 can be pushed to one side somewhat if necessary, as they have to be adjusted in position subsequently. By winding the filament round 90 the roots of the lower scaffold wires, advantage is taken of the considerable rigidity offered by such scaffold wires at these points, it being impossible in most cases to wind the filament round the outer tips of the lower 95 scaffold owing to the resilience of the filament before flashing and the weak nature of the wires 4 and, further, as the filament afterwards shrinks, allowance should be made for the shorter length of the loops which the 100 wire will then assume, and by winding the wire obliquely from the outer tips of the upper scaffold to the inner roots of the lower scaffold the diagonal length thus imparted to the loops approximately corresponds to 105 the increased length which is required in the loops to allow for their subsequent contraction when flashed, and when engaging the outer tips of the lower scaffold.

In order to form hooked ends on the upper 110 leading-in wires, an instrument Figure 5 is provided consisting of a tubular stem 17 in which is slidably mounted an inner rod 18 having a manipulating button or ring 19 at the outer end, the other ends of the tubular 115 stem and the inner rod being formed as a knife edge 20 and double jaw 21 so that when engaged over the leading-in wires 6, 6^a and the jaws closed, a hook end is formed. A modification of this instrument with the jaws 120 reversed to form a downward hook is necessary for putting hooked ends on any of the lower scaffold wires 4 which may have become damaged.

An instrument suitable for closing the 125 open hooked ends of the leading-in wires in order to nip the filament is shown in Figure 6 where the pivoted jaws 7 and 8 are carried at the end of a long stem 10 so that the instrument may be inserted readily through 130

the aperture 1. A corresponding instrument is shown in Figure 7 suitable for cutting the bights *a*, *d* of the filaments, the shears 11 being actuated at the end of a long stem 12 5 from the handles 13.

By forming the aperture 1 as shown slightly out of centre towards the side of the lamp opposite the leading-in wires, a greater facility is obtained in passing up the instruments to treat the ends of the leading-in 10 wires 6, 6^a, this eccentricity of the aperture enabling the instrument to clear the lower bead 14 on the glass stem 15.

What we claim as our invention and desire to secure by Letters Patent is:—

1. The process of renewing the metallic filament upon the permanent supports within an electric incandescent lamp without removing them from the bulb, comprising 20 making an opening in the bulb, winding the new filament directly round the upper permanent scaffold wires and the roots of the lower permanent frail scaffold wires, setting the filament, then moving the depending 25 loops of the filament from the roots to the outer ends of the lower scaffold wires.

2. The process of renewing the metallic filament upon the permanent supports within an electric incandescent lamp without removing them from the bulb, comprising 30 making an opening in the bulb, bending down the lower permanent scaffold wires near the roots, winding the new filament directly round the upper permanent scaffold 35 wires and the roots of the lower permanent frail scaffold wires, setting the filament, then bending back such frail wires to their original position and moving the depending loops of the filament from the roots to the outer ends of the lower scaffold wires.

3. The process of renewing the metallic filament upon the permanent supports within an electric incandescent lamp without removing them from the bulb, comprising 45 making an opening in the bulb, forming an open hooked end on one leading-in wire,

winding the filament several turns round the hook and leaving a stretch or bight of the filament from the wound hook to the other leading-in wire, closing the hook and cutting 50 such bight, winding the new filament directly round the upper permanent scaffold wires and the roots of the lower permanent frail scaffold wires, setting the filament, then moving the depending loops of the filament 55 from the roots to the outer ends of the lower scaffold wires.

4. The process of renewing the metallic filament upon the permanent supports within an electric incandescent lamp without removing them from the bulb, by forming an aperture in the base of the lamp bulb disposed substantially eccentric to the axis of the glass stem to enable the implement used in rewiring to be passed into the bulb clear 60 of the usual lower bead on the glass stem, winding the new filament directly round the upper permanent scaffold wires and the roots of the lower permanent frail scaffold wires, setting the filament, then moving the depending 65 loops of the filament from the roots to the outer ends of the lower scaffold wires.

5. The process of renewing the metallic filament upon the permanent supports within an electric incandescent lamp without removing them from the bulb, comprising 70 making an opening in the bulb, placing the new filament on the upper permanent scaffold wires and round the lower permanent frail scaffold wires at points removed from 75 their outer ends, setting the filament and then moving the depending loops of the filament to the outer ends of the lower scaffold wires.

In testimony whereof we have signed our 80 names to this specification in the presence of two subscribing witnesses.

SYDNEY COXON.

WILLIAM ALBERT WILLIAMS.
